US00D473204S

(12) United States Design Patent **(10) Patent No.:** **US D473,204 S**
Tanio **(45) Date of Patent:** **** Apr. 15, 2003**

(54) VOICE RECORDER AND PLAYER

D426,223 S * 6/2000 Nomura D14/167
D453,752 S * 2/2002 Lee D14/192
D457,872 S * 5/2002 Tanio D14/167

(75) Inventor: **Satoru Tanio, Hachioji (JP)**

* cited by examiner

(73) Assignee: **Olympus Optical Co., Ltd., Tokyo (JP)**

Primary Examiner—Nanda Bondade
(74) Attorney, Agent, or Firm: Hogan & Hartson, LLP

(**) Term: **14 Years**

(57) CLAIM

(21) Appl. No.: **29/159,626**

The design for voice recorder and player, substantially as shown and described.

(22) Filed: **Apr. 24, 2002**

DESCRIPTION

(30) Foreign Application Priority Data

Nov. 6, 2001 (JP) 2001-032699

FIG. 1 is a front view.

(51) LOC (7) Cl. **14-01**

FIG. 2 is a left side view.

(52) U.S. Cl. **D14/167; D14/168**

FIG. 3 is a right side view.

(58) Field of Search **D14/156-157,**

FIG. 4 is a top plan view.

D14/160-165, 167-168, 188-189, 217-218,

FIG. 5 is a bottom plan view.

299, 496; 312/7.1; 369/75.1, 75.2, 77.1,

FIG. 6 is a rear view; and,

77.2; 455/344, 346-351

FIG. 7 is a right, top, front perspective view.
